UNITED STATES PATENT OFFICE.

HENRY E. WALLIS, OF TERRE HAUTE, INDIANA.

ROTARY GRATE FOR FURNACES.

945,825.

Specification of Letters Patent. Patented Jan. 11, 1910.

Original application filed January 8, 1907, Serial No. 351,349. Divided and this application filed September 26, 1907. Serial No. 394,696.

To all whom it may concern:

Be it known that I, HENRY E. WALLIS, of Terre Haute, in the county of Vigo and State of Indiana, have invented certain new and useful Improvements in Rotary Grates for Furnaces, of which the following is a specification.

The object of the present invention is to produce a rotary grate, especially intended 10 for steam boiler furnaces, which shall always rotate freely and easily in such a way as not to be affected by accumulating ashes; and which shall involve a minimum of obstruction on its under side.

15 This application is a division of application filed January 8, 1907, Serial Number 351,349.

The improved grate is illustrated in the accompanying drawings in which—

20 Figure 1, is a horizontal section through a furnace showing a plan view of the grate, parts being broken away and only a portion of the grate sections being shown. Fig. 2, is a central vertical section of the grate.

25 Fig. 3, is an enlarged section of one side of the grate. Fig. 4, is a detail plan view of the central portion of the truss spider.

The rotary grate is composed of grate sections *g*, each of sector shape, and each 30 having a plurality of separate grate bars furnishing air spaces for the upward passage of air from the ash-pit *H*, beneath through the fuel on the grate to the combustion chamber *D*, above, and also providing for the downward passage of the ashes. The outer margins of the grate sections are 35 supported upon an annular bull-ring *I*. This bull-ring has integral loops *h*, with which lugs on the grate sections coöperate,

40 as shown in Fig. 2. The inner ends of the grate sections are supported upon a truss-spider consisting of truss-bars *J*, which meet at the center and each of which has at its outer end a bent end to engage an integral loop *i*, on the bull-ring. This construction of rotating grate involves the minimum obstruction on the underside of the grate. The lower edge of the bull-ring is 45 stiffened by a ratchet-ring *K*, bolted thereto having ratchet-teeth on its outer periphery.

This ratchet-ring may coöperate with any suitable driving mechanism whereby rotary motion may be communicated to the grate. The original application filed January 8, 55 1907, of which the present application is a

division, illustrates and describes appropriate mechanism for giving rotary movement to the grate.

It is important that the grate should always rotate freely and easily and in such a way as not to be affected by accumulating ashes. To this end the construction illustrated is employed. The bull-ring *I*, is located wholly beneath a fixed dead-plate *N*, and the dead-plate is as close to the bull-ring as free rotation will permit. The bull-ring is rotatively located upon a fixed ash-ring *O*, and the construction of ash-ring and bull-ring is such as to provide a race-way 30 for anti-friction balls *P*. As the result of 35 this construction the bull-ring turns on ball bearings and hence is readily and easily rotated. The ball race is provided by the co-operative constructions of the bull-ring and ash-ring respectively, as best shown in Fig. 75 40 3. The bull-ring has a horizontal flange *m*, an inner vertical wall *n*, and outer vertical wall *p*. Similarly, the ash-ring *O*, has a bottom *r*, inner vertical wall *s*, and outer vertical wall *t*. The balls rest on the bottom 45 *r*, of the ash-ring and the flange *m*, of the bull-ring rests on the balls. As shown in Fig. 3, the outer wall *t*, of the ash-ring extends above the center of the balls; while the inner wall of the bull-ring extends below 50 the center of the balls. This is an important feature, taken in connection with the vertical character of these walls, since it prevents the climbing up of the balls, due to their outward thrust, which would cause the bull-ring to bind and hence fail to rotate.

With the construction shown the grate always rotates freely and attention is reduced to the minimum.

The ratchet-ring *K* constitutes the drive-ring for the rotary grate. It is carried by the bull-ring and is located below the ball-race. It is peripherally driven through the ratchet-teeth on its outer surface, so that the bull-ring is peripherally driven around and 95 around in the same direction. The ball-race is hence a continuous peripheral race formed by complete peripheral grooves in the bull-ring and ash-ring respectively.

I claim—

1. The rotary grate comprising the annular bull-ring, the truss-spider, consisting of radial truss-bars which meet at the center and are there connected together, each truss-bar at its outer end being connected to and 100 110

105

supported by the bull-ring, and the grate sections supported at their outer ends by the bull-ring and at their inner ends by the united inner ends of the truss-bars.

- 5 2. The rotary furnace grate comprising a peripherally driven bull-ring which is rotated around and around in the same direction, in combination with the ash-ring, said bull-ring and ash-ring being mutually 10 formed with complete peripheral grooves to provide a continuous ball-race for antifriction balls on which the bull-ring rests, a fixed dead-plate covering the ash-ring and bull-ring, and as close to the bull-ring as the 15 ready rotation thereof admits, and a drive-ring carried by the bull-ring below the ball-race.
3. The combination of the peripherally

driven bull-ring and the ash-ring of a rotary furnace grate with a continuous peripheral ball-race formed partly in both, the inner wall of the portion of the race formed by the bull-ring being substantially vertical and extending below the center of the balls, and the wall of the ash-ring constituting the 25 outer wall of the ball-race being also vertical and extending above the center of the balls, and a drive-ring carried by the bull-ring below the ball-race.

In witness whereof, I have hereunto signed 30 my name in the presence of two subscribing witnesses.

HENRY E. WALLIS.
